UNITED STATES PATENT OFFICE.

ARTHUR YANCEY, OF BILOXI, MISSISSIPPI.

SEINING APPARATUS.

No. 919,109.

Specification of Letters Patent.

Patented April 20, 1909.

Application filed April 24, 1906, Serial No. 313,475. Renewed August 5, 1908. Serial No. 447,139.

To all whom it may concern:

Be it known that I, ARTHUR YANCEY, a citizen of the United States, residing at Biloxi, in the county of Harrison and State of Mississippi, have invented certain new and useful Improvements in Seining Apparatus; and I do hereby declare the following to be a full, clear, and exact description of the invention, such as will enable others skilled in the art to which it appertains to make and use the same.

This invention relates to improvements in seining apparatus.

Broadly speaking, the invention consists in providing means for bringing together the lead lines of a seine while the seine is being hauled and landed, and the particular object of the present invention is to provide means for facilitating this operation by reducing the friction of the seine on the operating parts.

Other objects of the invention consist in providing improved means for mounting the depending arm, hereinafter referred to, whereby the same may be readily elevated; also by the disposition of the closing rollers to provide means for the passing of shells as the seine is being hauled; also in providing improved mechanism coöoperating to haul the seine.

Other objects and advantages will appear from the following description, and while the invention is not restricted to the specific details illustrated and described, still for the purpose of disclosure, reference is had to the accompanying drawings, showing practical embodiments of the invention and in which,

Figure 1 is a plan view of the apparatus set in operative position, parts being broken away for clearer illustration. Fig. 2 is a sectional elevation on the line 2—2 of Fig. 1, the webbing and cork lines for the seine being omitted and the side stay of the guard net being shown in elevation its full length. Fig.

3 is a fragmentary view in detail of the upper end of the depending arm, showing means for interlocking same to its rock shaft. Fig. 4 is a fragmentary sectional view through one of the boats on the line 4—4 of Fig. 2 and looking in the direction of the arrows. Fig. 5 is

a plan view of a modified form of sled block and rollers thereon, the depending arm being broken away. Fig. 6 is a view in side elevation, looking toward the right in Fig. 5, and Fig. 7 is a transverse section on the line 7—7 of Fig. 5, but showing the upper and lower

rollers corresponding to the vertical rollers hereinafter referred to mounted on horizontal axes instead of on vertical axes.

Referring particularly to Figs. 1, 2, and 4, A and A' designate a pair of floating supports preferably in the nature of detachably connected boats. a and b are the propeller shafts thereof, and c are countershafts extending adjacent one side of each of said boats, for instance by chain and sprocket c⁰ to the propeller shafts. Carried by each counter shaft c are a plurality of worms c¹ meshing with worm wheels c² mounted on the stud shafts c³ journaled in the spaced plates c⁴ c⁵. These stud shafts c³ project through the plate c⁵ and keyed or otherwise secured thereon are grooved wheels or sheaves c⁶ c⁷. Interposed between and arranged above each pair of grooved wheels is an idler roller d provided with a circumferential groove disposed in alinement with the grooves of said wheels. As shown, the worm wheels and gear are housed by the plates c⁴ and c⁵ and suitable top plates c⁸ and end plates. At the rear of each boat is suitably journaled the transversely disposed landing roller e, the inner end of which is provided with an annular groove or guide-way adapted to aline with the grooved wheels aforesaid. Transversely disposed at the rear of one of said boats and projecting beyond the side thereof is a rock shaft f at the projecting end of which is mounted the depending arm g preferably provided at its lower portion with a yoke member comprising spaced arms g' adapted to be pivotally connected with a sled block hereinafter referred to. It is preferable that the upper end of the rod g be interlockingly connected to the rock shaft f in such manner that when unlocked it will be capable of longitudinal movement. Any suitable means may be employed for accomplishing this, and for the purpose of illustration I have shown the end of the shaft f as being provided with hollow T member f' slotted at one or more positions indicated at f² to receive a pin or connecting screw f² secured to sleeve f³ in which the depending arm g is adapted to slide. This sleeve is provided with longitudinal and transverse slots f⁴ and f⁵, respectively, which coöperate with the pins f⁶ carried by the arm g to form a bayonet joint therewith.

H designates a triangular guard of netting adapted to extend from the sled block to

either side of the boats, forming a barrier for the corralled fish at the opening formed by the lead lines extending upwardly from the bed of the stream to the boats. This 5 barrier comprises the transverse cable h and the side cables h^2 secured at their lower ends to the yoke g' , the upper end of the guard being adapted to be detachably secured by suitable eyes h' on both boats. The webbing 10 of the guard or barrier is preferably provided with a plurality of rings h^3 adapted to slidably encircle the arm g . It will be observed also that these side cables h^2 act as stays to prevent the skewing of the lower 15 portion of the depending arm and hence holding the sled block rigidly against lateral movement.

1 designates a simple form of sled block and suitably mounted thereon is the trans- 20 verse or horizontal spindle 2 comprising the axis of a pair of horizontal rollers 3. It will be observed that by the use of the expression "horizontal rollers," I mean rollers mounted on horizontal axes, and by the ex- 25 pression "vertical rollers," rollers mounted on vertical axes. As shown, these guiding rollers (which for purposes of description will also be referred to as the horizontal or guiding rollers) are preferably of an elongated form having an inner neck portion and flaring outwardly, the object being that the increasing traction surface toward the outer end will assist in overcoming the oblique pull on the web of seines hauled by operating 30 the lead lines. The outer ends of the spindles 2 extend beyond the rollers 3 and mounted thereon are the hemispherical caps or idler rollers 4 revoluble independently of the rollers 3 and adapted to prevent the 35 winding or tangling of the webbing on the rollers 3 when the net is washed against them by transverse currents.

It will be observed that the arms of the yoke member g' are pivotally connected to 45 the sled block on an axis co-incident with the axis of the horizontal rollers. In the drawings they are illustrated as being pivotally secured to the axis or axes of the horizontal rollers.

50 Forward of the horizontal rollers and spaced therefrom are a pair of closing rollers 5 adapted to rotate on vertical axes and hereinafter referred to as the vertical or closing rollers. These rollers may be of any suitable 55 form, but are preferably of the form shown in Fig. 2 as comprising a spherical portion with a short shank or neck forming a groove or guideway for guiding the lead lines of the seine. It may be also preferable to provide 60 the pivoted locking buttons 6 having their free ends adjacent the rollers 5 and which are adapted to co-operate with said rollers to prevent the lead lines from being disengaged from said rollers in a laterally inward direction. As shown, these buttons may be held

apart by any suitable interposed spring 7, and may also be provided with a slot 8 co-operating with a pin 9 on the sled block to limit their movement toward the vertical 70 rollers.

In the modification shown in Figs. 5 to 7, the sled block comprises the base portion 7^a provided on its bottom with a metallic reinforcing plate 8 and also provided with the spaced upright supports 7^a on which are suitably journaled the horizontal rollers. 9 is a transverse member disposed above said horizontal rollers and hinged as at 10 to said upright member 7^a . The member 9 is provided with a recessed portion 9^a . Extending forwardly of the cross member 9 is the transverse plate 11 pivotally supported by the pin 11^a and the interposed spacing blocks 11^b shown more clearly in Fig. 7. This transverse member 11 is provided with a recess 85 adjacent the recess 9^a and having a locking button 11^c co-operating therewith. The plate 11 is also provided with the slots 12 circumferentially disposed with relation to the pivot 11^a, in which slots are projected the tying 90 bolts 13 allowing the member 11 to swing on the pivot 11^a within the limits of the length of said slots. Depending from the member 11 is a roller 14 adapted to rotate on the vertical pivot 15. As shown this roller and pivot 95 may be suitably incased as at 16. Similarly, on the base portion 7^a is also mounted a roller 17, similarly incased, and this roller may be mounted in any suitable way such as on a horizontal axis as shown. In Fig. 7 both 100 of the rollers 14 and 17 are for the purpose of illustration shown as operating on horizontal axes 15^a.

In Figs. 5 to 7, the horizontal rollers proper or the rollers designed to direct the lead lines 105 to the boat, are of a slightly different construction from that illustrated in Figs. 1 and 2. In this form the rollers 18 are of a substantially spheroidal form provided with the grooved neck portion 18^a (Fig. 7), are hollow 110 and provided with a central bore through which passes a spindle 19 provided with the screw-threaded shank 20 and held in position by suitable nuts. 21 designates metallic wear plates carried by the upright supports 7^a . 115 In this construction it will also be seen that instead of providing a single spindle 2 for the horizontal rollers, these horizontal rollers are mounted on separate spindles 20 and it will also be noted that the arms g' of the yoke 120 loosely engage the shank end of the spindles.

In Fig. 1 the web B of the seine is shown intact throughout with the web of the barrier broken away on that side for clearness of illustration, while the web B' is shown 125 broken away, disclosing more clearly the web of the barrier.

Referring to Figs. 1 to 4, with the cork line C and the lead lines D set as shown, it will be observed that the seine is ready for 130

hauling. Power being applied to the shafts *a*, motion is transmitted to the shafts *b* which through the worm gearing rotate the sheaves *c*⁶ *c*⁷ and the lead lines of the seine 5 passing beneath these sheaves and over the idler *d* are drawn in, guided upwardly by the rollers 3, having first passed around the closing rollers 5 from the outwardly diverging direction bounding the area of the 10 set seine. At the same time as the lead lines are being hauled in, it will also be observed, as previously mentioned, that the surface presented to the lead lines by the restricted portion of the rollers 3 being of 15 lesser diameter than that presented to the webbing, the forward rollers are cleared by hastening the movement of the web in counteraction of the oblique traction of the net when the seine is hauled by the lead 20 lines, which is an important feature. Also it will be seen that as the seine is being hauled, the webbing at the rear end of the boat is symmetrically passed over the landing rollers *e*. It will also be seen that if it is 25 desired to elevate the sled block for any reason, for instance when the bag of the seine has been reached, the sleeve *f*³ is slightly rotated to permit the pins *f*⁴ to come into alignment with the slot *f*⁴ when 30 the depending arm *g* may be slid longitudinally through the sleeve *f*³, and this may the more readily be done by any suitable connection between the power actuating means and the sled block. This would be accomplished when the pocket of the seine reaches 35 the rollers 5 upon continued winding up of the lead lines.

In referring to Figs. 5 to 7 after the school of fish have been surrounded, the 40 operators lock the lead lines in the closing rollers by releasing the hinged member 9 and swinging the member 11 on its pivot 11^a through an angle sufficient to separate the rollers 14 and 17 to receive the lead lines. 45 The member 11 is then swung around to its initial position and the hinged member 9 locked in its normal position by the locking button 11^c, when the depending arm with the sled block is put overboard, with the 50 lead lines of course also passing beneath the grooved portion or neck 18^a of the rollers 18.

Having thus described the invention, what I claim is:

1. In seining apparatus, the combination with a plurality of rollers to guide together the lead line of a seine for closing the webs of same, of a plurality of rollers to direct said lead line toward the surface of the water.
2. In seining apparatus, the combination with a sled block, of a plurality of closing rollers mounted thereon and adapted to converge the lead lines of a seine in a substantially horizontal direction for closing the 65 webs thereof, and a plurality of guiding

rollers adapted to direct said lead lines upwardly from their horizontal plane of convergence.

3. In seining apparatus, the combination with a sled block, of a plurality of closing 70 rollers mounted thereon adapted to converge the lead lines of a seine in a substantially horizontal direction for closing the webs thereof, a plurality of guiding rollers adapted to direct the lead lines upwardly 75 from their horizontal plane of convergence, a support, and a depending arm carried by said support and pivotally connected to said sled block on an axis coincident with the axis of said guiding rollers. 80

4. In seining apparatus, the combination of means for converging and directing upwardly the lead lines of a seine, comprising a plurality of sets of suitably mounted closing and guiding rollers, said sets of rollers 85 being spaced apart to allow of the passage of foreign matter apt to tangle in the web adjacent the lead lines.

5. In seining apparatus, the combination of means for converging and directing upwardly the lead lines of a seine, comprising 90 horizontal guiding rollers and suitably mounted closing rollers.

6. In seining apparatus, the combination of means co-operating to converge and direct 95 upwardly the lead lines of a seine containing as elements a horizontal guiding roller and a vertical closing roller.

7. In seining apparatus, the combination of means co-operating to converge and direct 100 upwardly the lead lines of a seine containing as elements a horizontal guiding roller and vertical closing rollers disposed forward of and spaced from said horizontal roller.

8. In seining apparatus, the combination 105 with a support located adjacent the surface of the water, an arm depending from said support, a shoe suspended by said arm, closing means and guiding means for the lead lines of a seine carried by said shoe, and side 110 stays extending from said support to the lower end of said arm for holding the latter rigid against lateral movement.

9. In seining apparatus, the combination with a support located adjacent the surface 115 of the water, an arm depending from said support, a shoe suspended by said arm, closing means and guiding means for the lead lines of a seine carried by said shoe, side stays extending from said support to the lower end of said arm for holding the latter 120 rigid against lateral movement, and webbing extending between said side stays for forming a barrier.

10. In seining apparatus, the combination 125 with a support located adjacent the surface of the water, an arm depending from said support, a shoe suspended by said arm, closing and guiding means for the lead lines of a seine carried by said shoe, side stays extend- 130

ing from said support to the lower end of said arm for holding the latter rigid against lateral movement and webbing extending between said side stays for forming a barrier 5 and provided with rings loosely encircling said depending arm.

11. In seining apparatus, the combination of a support, of a longitudinally movable depending arm carried by said support, means 10 for locking said arm against longitudinal movement, and means carried by the lower end of said arm for converging and leading upwardly the lead lines of a seine.

12. In seining apparatus, the combination 15 with a support, of a rock shaft carried by said support, a sleeve carried by said rock shaft at right angles thereto and so mounted as to be capable of limited axial rotation, said sleeve being provided with an axial and a 20 circumferentially disposed slot communicating with each other, a depending arm slidably mounted in said sleeve, a pin carried by said arm and coöperating with said slots to unlock and interlock said arm and sleeve, and 25 means carried by the lower end of said arm for converging and leading upwardly to said support the lead lines of a seine.

13. In seining apparatus, the combination 30 with a support, of a plurality of sheaves carried by said support, an idler roller interposed between said sheaves, said sheaves

and roller being adapted to engage the lead lines of a seine at opposite positions to their circumference, means for simultaneously operating said sheaves in the same direction 35 of rotation, and means coöperating to converge and lead upwardly the lead lines of a seine in a substantial plane of alignment with said sheaves.

14. In seining apparatus, the combination 40 with a sled block comprising a base support and a member pivoted to turn horizontally thereon, a slot and pin connection between said pivoted member and support to limit the swing of the former, means for locking 45 said pivoted member in position, and closing rollers carried by said sled block and pivoted member.

15. In seining apparatus, the combination 50 with a sled block, of horizontal guiding rollers journaled thereon, a hinged member disposed above said guiding rollers, a pivoted member forward of said hinged member, means for locking said hinged and pivoted members together, and closing rollers carried 55 by said sled block and pivoted member.

In testimony whereof, I affix my signature, in presence of two witnesses.

ARTHUR YANCEY.
